EXPLODING TOY VEHICLE

Joseph L. Bonanno, South Orange, N.J., assignor to The Lionel Corporation, New York, N.Y., a corporation of New York

Filed Jan. 20, 1960, Ser. No. 3,560
4 Claims. (Cl. 273—102.1)

The present invention relates in general to model railway cars and in particular to a railway car capable of simulating the results of an explosion.

In one form of the invention a toy railroad freight car with removable sides and roof portions is provided. The car bed has mounted thereon a spring biased impulse arm which is capable of being cocked and latched in a loaded position. The car bed also contains stationary end portions which provide a support for a slidably engaged car roof. In operation a side wall of the toy railroad car is loosely placed in an upright position and is capable of inward pivotal motion to trigger the impulse arm unlatching mechanism. The release of the impulse arm will successively knock off the car roof and sides to thereby realistically simulate the effect of either an internal car explosion or the direct hit by a projectile.

A safety locking bar or pin is provided to prevent accidental tripping of the spring biased impulse arm by the movable side wall during periods when it is not desired that the railroad car explode. When operation of the impulse mechanism is desired it is merely necessary to remove the locking bar, whereupon a direct hit by a missile or severe jarring over bumpy tracks will cause the realistic simulation of the car's destruction.

The invention provides a novel combination of parts releasably secured to a car bed and employs an impulse arm latching mechanism which cooperates with a movable side wall of the car to effectuate triggering of the impulse arm mechanism.

The invention also provides a novel cooperation between the safety bar mechanism and the impulse arm latching mechanism.

An object of the invention is, therefore, to provide a toy car capable of simulating the result of an explosion.

Another object of the invention is to provide a model railway car which contains a spring biased impulse mechanism and removable sides and roof portions.

A still further object of the invention is to provide a collapsible model railway car which, after collapse, is capable of easy reconstruction and resetting so that a second simulated explosion may be performed.

Another object of the invention is to provide a collapsible toy body which is simple in design, realistic and neat in appearance, simple and durable in construction and economical to manufacture.

For a better understanding of the nature of the invention, reference should be had to the accompanying drawings in which:

FIG. 1 is an exploded perspective view of the invention;

FIG. 2 is a top plan view of the invention with the car roof removed;

FIG. 3 is a bottom plan view showing the underside of the car roof;

FIG. 4 is a partial cross sectional view taken along line 4—4 of FIG. 2 showing the safety bar in position and the impulse arm cocked and latched;

FIG. 5 is a cross sectional view taken along line 5—5 of FIG. 2;

FIG. 6 is a partial section of the invention showing the impulse arm positioned at the instant of contact with the car side during its release movement;

FIG. 7 is a cross sectional view taken along line 7—7

2

of FIG. 6 and showing the sequential movement of the car sides and roof;

FIG. 8 is a cross sectional view of the car with the impulse arm in a fully extended position and the removable roof and sides in motion;

FIG. 9 is a partial view showing the lower side of a car base employing an alternate arm latching embodiment; and

FIG. 10 is a partial cross sectional view taken along line 10—10 of FIG. 9.

Referring to FIG. 1, a car 10 is shown in exploded fashion with the roof 12 in an artificially raised position. A trigger side wall 14 is provided with locating studs 40 which cooperate with the apertures 38 in a car bed 18 to locate the bottom edge of the trigger side wall 14 along the car bed. Similarly, an opposite side wall 16 is provided with locating studs 40 which cooperate with respective apertures 38 in the car bed 18 to locate its lower edge. The spacing between the locating studs 40, 40 on each side wall differs so that their position on the car bed cannot be interchanged. The upper edge of each car side wall is provided with an outward movement restraining catch 46 which is engageable with a pad portion 47 on the underside of the roof 12. The car 10 is slidably engageable with the forward and rear car ends, respectively, 20 and 22. Irreversible roof orientation is obtained with respect to the car bed by the provision of tongue portions 42 and groove portions 44 on the inner side of the car ends. It should be noted that the forward car end has a thicker tongue and associated groove than the rearward car end, thereby accomplishing this one way orientation of the roof to the car bed. When the car roof is placed atop the car ends, the sides of the car may be assembled by the placement of the studs 40 in their respective apertures 38 and the upward pivoting of the car sides so that the side catches 46 slidably engage the roof pads 47. The car ends 20 and 22 are rigidly secured to the bed portion 18 and are provided on one side with a wall retaining flange 23. This retaining flange acts to prevent further inward motion of the wall 16.

Mounted upon the car bed is an impulse mechanism shown generally at 24. This mechanism comprises an impulse arm 26 pivotally mounted on flanges 29 which are formed from punched portions of the car bed 18. The impulse arm 26 is biased by a coil spring 28 so that the free end of the arm has a rest position toward the forward end of the car. An arm latch 30 is mounted on a pivot 36 which is formed from bed 18. The arm latch 30 has a sear portion 34 cut into an edge thereof at a point above the pivot point 36. Integral with the latch 30 is a safety bar locking flange 32 which also provides a trigger or release surface which is operated by the inward motion of the car side wall 14 to thereby release the impulse arm from the sear 34.

An aperture 54 in the roof 12 is in vertical alignment with a similarly sized aperture 56 in the base 18. These apertures are spaced so that after cocking of the impulse arm 26 a pin 52 may be inserted downward through the apertures to thereby restrain any motion of the trigger release surface 32. In this manner, the cocked impulse arm mechanism will not be accidentally set off by normal jarring. The side wall 14 has an inwardly projecting trigger shelf 15 which extends for a substantial distance longitudinally along the side wall and in close proximity to the trigger flange 32 of the arm latch 30. The shelf 15 acts to limit inward motion of the trigger side wall 14 by light abutment against the flange 32 when the safety bar 52 is in place. When the safety bar is removed inward motion of the shelf 15 will cause release of the impulse arm. The horizontal inner edge portion 15a of the shelf

15 cooperates with an oblique portion 25 of the impulse arm 26 during the arm release to project the side 14 up and outwardly. FIG. 6 illustrates the initial contact made by the oblique portion 25 upon release of the impulse mechanism. This oblique camming surface acts to outwardly and upwardly push the trigger wall at approximately the same instant that the roof is first being contacted by the free end of the impulse arm 26. It can be readily seen that upon the release of the impulse arm with the subsequent jarring of the roof and trigger wall from the car that the remaining side wall will be unsupported and shaken from its position. This latter wall removal is aided by the inertia of the latch corner 58 contacting the side wall 16.

In operation it can easily be seen how a very realistic simulated explosion may be accomplished using the mechanism of the car previously described. To construct the car the impulse arm is latched in a cocked position and the roof is properly indexed and gently laid in place upon the car end portions. The locking bar 52 is next inserted into the aligned apertures 54 and 56 to thereby engage the flange 32 and prevent accidental tripping of the impulse mechanism. The side walls 14 and 16 are then next located along their lower edges on the sides of the car bed and pivotally raised into a vertical position to engage the edge portions of the car roof. In this condition the railroad car presents a very normal, structurally complete, appearance and for realism purposes may be externally marked "explosives," "handle with care," "do not jar," etc.

When a simulated explosion is desired the safety bar need only be removed and the trigger wall urged inward to release the impulse arm.

Referring to FIGS. 9 and 10 another form of the invention is shown wherein an impulse arm latch 64 has a depending sear portion 66 extending beneath the car bed 18. In this embodiment an external safety lever 60 is pivoted beneath the car bed on a rivet 68. The safety lever has an outer end protruding beyond the car side to allow easy access to the train operator while the inner end is provided with a locking ear portion 62 which engages the latch sear 66 to prevent accidental release of the impulse arm 26. In the position shown in FIG. 9 the safety lever 60 is in a locking position and it can readily be seen how a small clockwise motion thereof will arm the impulse mechanism to ready the car for a simulated explosion.

Although the invention has been described in the preferred embodiment of a railroad car, it is equally suitable for simulating an explosion in any toy vehicle, such as a toy truck or automobile. The conventional railroad truck portion shown in dotted lines beneath the car bed 18 is included for illustrative purposes only.

While a specific embodiment of the invention has been shown and described in detail to illustrate the application of the invention principles, it will be understood that the invention may be embodied otherwise without departing from such principles.

What is claimed is:

1. A model railroad car capable of simulating the effect of an explosion comprising a car bed, upstanding car ends secured on said car bed, a car roof slidably secured to said car ends, a spring biased impulse arm pivotally secured to said car bed and of a length greater than said car roof to car bed clearance distance, impulse arm latching means on said car bed to hold said arm in a pre-cocked position, a first side wall resting upon a longitudinal edge of said car bed adapted to pivot inwardly about the longitudinal edge of said car bed, means temporarily engaging said first car side wall upper edge with said car roof to prevent outward motion thereof, a second car side wall resting upon a longitudinal edge of said car bed, means

upon said car ends temporarily restraining inward movement of said second side wall, means upon said car roof temporarily restraining outward movement of said second car wall, and impulse arm unlatching means positioned in close adjacent relation to an upper inside portion of said first side wall so that said means is actuated by inward movement of said first car side wall whereby said spring biased impulse arm will be released from a cocked position and contact the car roof and the temporary restraint upon said car side walls will be removed.

2. A collapsible model railroad car comprising a car bed, upstanding immovably secured car ends mounted on said car bed, first and second removable car sides, positioning means on the lower edge of said first and second car sides engageable with said car bed, said positioning means allowing both inwardly and outwardly pivotal movement of said car sides on said bed, a car roof supported by said car ends, an impulse arm pivotally mounted at one end of said car bed and of sufficient length when pivoted to contact said car roof, spring means biasing said impulse arm toward one end of said car bed, impulse arm latching means mounted on said car bed to hold said impulse arm in a cocked position, said impulse arm latching means including a portion in close adjacent relation to an upper inside portion of said first car side wall when in an arm latching position, positioning means upon said second car side wall maintaining it in a substantially vertical position in contact with said car bed and roof, and means on the upper edge of said first side wall engageable with said car roof to restrain outward movement thereof whereby upon inward motion of said first side wall a portion of said impulse arm latching means is contacted to thereby release said cocked impulse arm.

3. A model railroad car capable of simulating the effect of an explosion comprising, a car bed having a safety bar receiving aperture therein, upstanding car ends mounted on said car bed, first and second car sides, positioning means on the lower edge of said first and second car sides engageable with said car bed, said positioning means allowing both inwardly and outwardly pivotal movement of said car sides on said car bed, a car roof having a safety bar receiving aperture in vertical alignment with said car bed aperture, said car roof supported by said car ends, an impulse arm pivotably mounted on said car bed and of sufficient length when pivoted to contact said car roof, spring means biasing said impulse arm toward one end of said car bed, impulse arm latching means mounted on said car bed to hold said impulse arm in a cocked position, impulse arm unlatching means in close proximity to an upper portion of said first car side wall, positioning means upon said second car side wall maintaining it in a substantially vertical position in contact with said car ends, bed and roof, means upon the upper edge of said first side wall engageable with said car roof to restrain outward movement thereof whereby upon inward movement of said first side wall said impulse arm unlatching means is actuated to thereby release said impulse arm.

4. A toy model railway car capable of simulating the effect of an explosion according to claim 3, including in addition, manually operated safety means extending through the bed and roof apertures to engage said impulse arm and said arm unlatching means to prevent accidental release of said impulse means.
